UNITED STATES PATENT OFFICE.

WILLIAM M. DUNCAN, OF ALTON, ILLINOIS.

FURNACE.

1,365,668.

Specification of Letters Patent. Patented Jan. 18, 1921.

Application filed October 20, 1917, Serial No. 197,581. Renewed June 21, 1920. Serial No. 390,667.

To all whom it may concern:

Be it known that I, WILLIAM M. DUNCAN, a citizen of the United States of America, a resident of Alton, in the county of Madison, 5 State of Illinois, have invented certain new and useful Improvements in Furnaces, of which the following is a full, clear, and exact description, reference being had to the accompanying drawings, forming a part of 10 this specification.

This invention relates to improvements in furnaces, and more particularly to a furnace wherein the draft is created artificially by means of a fan, or the like. The main 15 object is to provide a simple and inexpensive means for removing ashes from the draft box, or boxes. Another object is to provide a very efficient draft producing apparatus. The new structure is particularly 20 adapted for use with a traveling chain grate.

In the preferred form of the invention, one or more draft boxes are arranged in a furnace below the fuel supporting elements of the grate, and these draft boxes are open 25 at the top for the discharge of air to the fuel. When the apparatus is in service, ashes dropping from the grate will fall through the openings in the top of the draft boxes and accumulate in said boxes. The 30 draft producing devices preferably include draft pipes leading from a fan or blower to the opposite ends of the draft boxes, and one of these pipes is provided with a normally closed ash outlet. Under ordinary 35 operating conditions, opposing air currents passing from the draft pipes flow into the opposite ends of the draft boxes under the grate, the air being discharged from the tops of the draft boxes to the fuel. To re- 40 move the ashes from the draft boxes, the ash outlet in one of the draft pipes is opened, and the blast of air passing from the other draft pipe is utilized to force the ashes from the draft boxes to the ash outlet, as will be 45 hereinafter described.

With the foregoing and other objects in view, the invention comprises the novel construction, combination and arrangement of parts hereinafter more specifically described 50 and illustrated in the accompanying drawings, wherein is shown the preferred embodiment of the invention; however, it is to be understood that the invention comprehends changes, variations and modifications 55 which come within the scope of the claims hereunto appended.

Figure I is a horizontal section taken through the furnace, showing the draft boxes and the conductors at opposite ends thereof, the chain grate being omitted. 60

Fig. II is a vertical section, partly in elevation, on a smaller scale, showing the endless chain grate, the draft producing device, and an ash car in a subway below the grate. 65

Fig. III is a vertical section taken approximately on the line III—III, Fig. II.

To illustrate the invention, I have shown a furnace provided with an endless chain grate A arranged between side frames 1 70 and fitted to wheels 2 and 3 at opposite ends of the grate. The wheels 2 are secured to a shaft 4, which may be actuated in any suitable manner to feed the chain grate. Draft boxes 5, surrounded by the chain 75 grate A, are open at the top as shown in Fig. II, for the discharge of air to the fuel. These draft boxes are arranged transversely of the grate and secured to the side frames 1. Dampers 6 (Fig. II), arranged in the 80 draft boxes, may be adjusted in any suitable manner to regulate the flow of air from the draft boxes to the grate. The draft at the different zones above the draft boxes can be varied by adjusting the dampers 6. 85

The draft producing means preferably comprises a fan or blower B, provided with a discharge member 7 having branches 8 and 9 for conducting the air to opposite sides of the grate structure. 10 designates 90 removable nipples connecting the branch conductors 8 and 9 to the opposite ends of the draft boxes 5. The side frames 1, which support the chain grate and draft boxes, are mounted on wheels 11 (Fig. II) so that 95 the grate structure can be readily moved into and out of the furnace. The nipples 10 (Fig. I) are fitted to the side frames 1, and these nipples can be easily removed from the side frames before removing the 100 grate structure from the furnace. To facilitate the removal of the nipples 10, openings 12 are formed in the conductors 8 and 9, said openings being normally closed to prevent the escape of the air under pressure. 105

Under normal operating conditions, the air passing from the fan B is discharged into the conductors, or draft pipes 8 and 9, and thereby conducted to the nipples 10 at the opposite ends of the draft boxes. The 110 opposing air currents flow in the directions indicated by the arrows shown in full lines

in Fig. I. A very effective draft is thus created, the pressure being substantially uniform throughout the draft boxes. The dampers 6 can be regulated to vary the draft at different zones transversely of the grate structure. The draft in a given zone above a draft box is substantially uniform throughout the zone, for the air currents are forced into opposite ends of the draft box, and a very effective draft is thus created in the draft box and at all points above the draft box.

The pipe or conductor 8 is provided with an ash outlet 13, normally closed by a door 14. An ash chute 15 leads from the outlet 13 to a point above a receptacle 16 in the subway under the furnace. This receptacle 16 is preferably in the form of a car, as illustrated diagrammatically in Fig. II. 17 designates a valve which normally occupies the open position shown in Fig. III, permitting the air currents to pass from the fan to both of the conductors 8 and 9.

Since the draft boxes 5 are open at the top, ashes dropping from the traveling grate will fall into said draft boxes and accumulate therein. Heretofore considerable difficulty has been experienced in removing ashes from draft boxes of this kind. My object is to provide an extremely simple and inexpensive means for removing the ashes.

In accordance with the preferred form of the invention, the ashes can be quickly removed from the draft boxes by merely closing the dampers 6 (Fig. II), moving the door 13 to the position shown by dotted lines in Fig. II, thus opening the ash outlet 13. The valve 17 is preferably moved to the position shown by dotted lines in Fig. III. When the parts are adjusted in this manner, the blast of air passing from the fan or blower B flows through the conductor 9, thence through the draft boxes 5, as indicated by dotted arrows in Fig. I, thereby forcing the ashes from the draft boxes, through the conductor 8, to the ash outlet 13 at the ash chute 15.

When the door 13 occupies the position shown by dotted lines in Fig. II, it closes direct communication between the fan and the upper portion of the conductor 8, and this upper portion of the conductor serves as means for conducting ashes from the draft boxes under the grate. The valve 17 (Fig. III) also serves as a closure for preventing direct communication between the fan and the conductor 8.

The door 14 at the ash outlet 13 is fixed to a shaft 20 provided with a sprocket wheel 21 (Fig. III). A sprocket chain 22 is fitted to the wheel 21 and also to a wheel 23 having an operating handle 24 which may be actuated to open and close the door 14.

I claim:

65 1. A furnace provided with a grate, a

draft box under the fuel supporting elements of said grate, said draft box having an opening for the discharge of air to the grate, a damper for regulating the flow of air from the draft box to the grate, a blast producing device, conductors leading from said blast producing device to said draft box so as to direct air under pressure from the blast producing device to the interior of said draft box, one of said conductors 75 being provided with an ash outlet for the discharge of ashes from said draft box, and a closure normally closing said ash outlet, said dampers and closure being adjustable to provide for the flow of air from one of 80 said conductors, through the draft box and thence to the ash outlet in the other conductor, thereby forcing ashes from the draft box to said ash outlet.

2. A furnace provided with a grate, a draft box under the fuel supporting elements of said grate, said draft box having an opening for the discharge of air to the grate, a damper for regulating the flow of air from the draft box to the grate, a blast 90 producing device, conductors leading from said blast producing device to said draft box so as to direct air under pressure from the blast producing device to the interior of said draft box, one of said conductors 95 being provided with an ash outlet for the discharge of ashes from said draft box, a closure normally closing said ash outlet, and a normally open valve adapted to place the last mentioned conductor out of direct communication with said blast producing device, said dampers, closure and valve being adjustable to provide for the flow of air from one of said conductors, through the draft box and thence to the ash outlet in the other 100 conductor, thereby forcing ashes from the draft box to said ash outlet.

3. A furnace provided with a grate, a draft box under the fuel supporting elements of said grate, said draft box having 110 an opening for the discharge of air to the grate, a blast producing device, conductors leading from said blast producing device to opposite ends of said draft box so as to provide means for discharging air under pressure into said opposite ends, one of said conductors being provided with an ash outlet at a point between said draft box and blast producing device, and a closure normally closing said ash outlet, said closure being 120 movable to an open position to provide for the discharge of air and ashes from the draft box in response to the action of said blast producing device.

4. A furnace provided with an endless 125 chain grate, draft boxes surrounded by said endless chain grate, said draft boxes being arranged transversely of the grate and being open at the top for the discharge of air to the fuel on the grate, dampers arranged 130

- in said draft boxes to regulate the discharge of air to the fuel, a blast producing device, conductors leading from said blast producing device to the opposite ends of said draft boxes so as to provide for the discharge of opposing air currents into the opposite ends of the draft boxes, one of said conductors being provided with an ash outlet for the discharge of ashes from the draft boxes, and a closure normally closing said ash outlet, said dampers and closure being adjustable to provide for the flow of air from one of said conductors, through the draft boxes, and thence to the ash outlet in the other conductor, thereby forcing ashes from the draft boxes to said ash outlet.
5. A furnace provided with an endless chain grate, a movable frame supporting said endless chain grate in the furnace, a draft box carried by said movable frame to provide for the delivery of air to the grate, said draft box having an intake formed in one side of said movable frame, a draft producing device comprising a relatively stationary air conductor leading to a point adjacent said intake in the side of said movable frame, and a slidable nipple forming a detachable connection between said stationary air conductor and said movable frame, said 20 slidable nipple being telescoped with said stationary air conductor and also with said intake in the side of said movable frame.
6. A furnace provided with an endless chain grate, a movable frame supporting said endless chain grate, in the furnace, said frame being removable from the furnace, a draft box carried by said movable frame and arranged transversely of said grate, said draft box being surrounded by said 25 endless grate to provide for the delivery of air to the fuel supporting surface, said draft box having an intake formed in the opposite side of said movable frame, a draft producing device comprising a relatively stationary air conductor leading to a point adjacent said intake in the side of said movable frame, and a slidable nipple forming a detachable connection between said stationary air conductor and said movable frame, said slid 30 able nipple being in the form of a short sleeve telescoped with said stationary air conductor and also with said intake in the side of said movable frame, said draft box also having an ash outlet formed in the opposite side of said movable frame, a relatively stationary ash receiver located adjacent to the last mentioned side of said movable frame, and a slid 35 able nipple telescoped with said ash receiver and also with said ash outlet so as to detachably connect said movable frame to said ash receiver.
7. A furnace provided with an endless chain grate, a movable frame supporting said endless chain grate, in the furnace, said frame being removable from the furnace, a draft box carried by said movable frame and arranged transversely of said grate, said draft box being surrounded by said endless grate to provide for the delivery of air to the fuel supporting surface, said draft box having an intake formed in the opposite side of said movable frame, a draft producing device comprising a relatively stationary air conductor leading to a point adjacent said intake in the side of said movable frame, and a slid 40 able nipple forming a detachable connection between said stationary air conductor and said movable frame, said slid able nipple being in the form of a short sleeve telescoped with said stationary air conductor and also with said intake in the side of said movable frame.

ducing device comprising a relatively stationary air conductor leading to a point adjacent said intake in the side of said movable frame, and a slidable nipple forming a detachable connection between said stationary air conductor and said movable frame, said slid 45 able nipple being in the form of a short sleeve telescoped with said stationary air conductor and also with said intake in the side of said movable frame.

7. A furnace provided with an endless chain grate, a movable frame supporting said endless chain grate, in the furnace, said frame being removable from the furnace, a draft box carried by said movable frame and arranged transversely of said grate, said draft box being surrounded by said endless 50 grate to provide for the delivery of air to the fuel supporting surface, said draft box having an intake formed in one side of said movable frame, a draft producing device comprising a relatively stationary air conductor leading to a point adjacent said intake in the side of said movable frame, and a slid 55 able nipple forming a detachable connection between said stationary air conductor and said movable frame, said slid able nipple being in the form of a short sleeve telescoped with said stationary air conductor and also with said intake in the side of said movable frame.

8. A furnace provided with an endless chain grate, a movable frame supporting said endless chain grate, in the furnace, said frame being removable from the furnace, a draft box carried by said movable frame and arranged transversely of said grate, said draft box being surrounded by said endless 60 grate to provide for the delivery of air to the fuel supporting surface, said draft box having an intake formed in one side of said movable frame, a draft producing device comprising a relatively stationary air conductor leading to a point adjacent said intake in the side of said movable frame, and a slid 65 able nipple forming a detachable connection between said stationary air conductor and said movable frame, said slid able nipple being in the form of a short sleeve telescoped with said stationary air conductor and also with said intake in the side of said movable frame.

9. A furnace provided with an endless chain grate, a movable frame supporting said endless chain grate, in the furnace, said frame being removable from the furnace, a draft box carried by said movable frame and arranged transversely of said grate, said draft box being surrounded by said endless 70 grate to provide for the delivery of air to the fuel supporting surface, said draft box having an intake formed in one side of said movable frame, a draft producing device comprising a relatively stationary air conductor leading to a point adjacent said intake in the side of said movable frame, and a slid 75 able nipple forming a detachable connection between said stationary air conductor and said movable frame, said slid able nipple being in the form of a short sleeve telescoped with said stationary air conductor and also with said intake in the side of said movable frame.

In testimony that I claim the foregoing I hereunto affix my signature.

WILLIAM M. DUNCAN.
